UNITED STATES PATENT OFFICE.

EZRA C. FITCH, OF NEWTON, MASSACHUSETTS.

WATCH-CASE PENDANT.

SPECIFICATION forming part of Letters Patent No. 424,191, dated March 25, 1890.

Application filed May 13, 1889. Serial No. 310,525. (No model.)

To all whom it may concern:

Be it known that I, EZRA C. FITCH, of Newton, in the county of Middlesex and State of Massachusetts, have invented certain new and useful Improvements in Safety Devices for Pendant-Setting Watches, of which the following is a specification.

Modern watches of the most approved form are so constructed that the hands can be moved by the pendant-crown, (which is used primarily for the purpose of winding the main-spring,) the engagement of operative parts with the dial-wheels being effected by giving an endwise motion to the winding-bar by pulling the crown outwardly from its winding position. While the extent of this outward motion of the crown is but slight, yet if the said movement or the pull be made easy there is a liability of the hands-setting mechanism being made operative by the watch-wearer in removing the watch from his pocket in case he should grasp the crown in so doing. If the pull be made sufficiently hard to obviate the before-mentioned liability, it may be found difficult for persons having but little strength in the fingers to pull sufficiently hard to move the crown outwardly, and thereby make the hands-setting mechanism operative.

My invention has for its object to enable the winding-bar and crown to be secured or held by the pendant bow or ring in its winding or inwardly-thrust position, and prevented thereby from being moved outwardly unless disengaged from the bow, so that the outward pull of the crown may be as easy as may be desired, the liability of accidental outward movement of the crown being prevented by the engagement of the crown with the bow.

To this end the invention consists in certain novel details of construction, to be hereinafter described and claimed.

Of the accompanying drawings, forming a part of this specification, Figure 1 represents a side elevation of a watch-pendant and its crown and bow, said crown and bow being engaged in accordance with my invention. Fig. 2 represents a sectional view of the same. Fig. 3 represents a sectional view of a modification.

The same letters of reference indicate the same parts in all of the figures.

In the drawings, *a* represents a watch-case pendant, and *b* represents the crown attached to the longitudinally-movable winding-bar *c*. *d* represents the bow, the ends of which are engaged with the sides of the pendant in the usual or any suitable manner, so that the bow can swing freely from side to side.

In carrying out my invention I form the bow *d* and crown *b* so that they can be interlocked in such manner that the bow will prevent outward movement of the crown. The preferred construction whereby this result is produced is that shown in Figs. 1 and 2, in which the bow is shown with an inwardly-projecting finger or stud *e* and the crown with a cavity or socket *f*, formed to receive said stud. It is obvious, however, that the projection can be formed on the crown and the receiving-cavity or socket in the bow, as shown in Fig. 3. The said stud and socket are relatively arranged so that when they are in engagement with each other the crown and winding-bar cannot be moved outwardly to the hands-setting position.

To make the engagement of the crown with the bow sufficiently firm, I provide a spring *i*, whereby the crown may be held with a yielding pressure against the bow, said spring pressing the crown outwardly to a sufficient extent to keep it in engagement with the bow and prevent it from falling away from the bow by its own weight when the pendant is in a vertical position. It is necessary that the crown and bow be arranged so that a slight outward movement of the crown will be required to engage with the bow, in order that the crown and bow may be disengaged by an inward movement of the crown, said outward movement being, however, insufficient to make the winding mechanism inoperative and the hands-setting mechanism operative.

The spring *i* is located between the crown and the end of the pendant, as shown in Fig. 2, the spring being a disk or strip curved to bear at its ends the pendant and the central portion on the hub of the crown, the spring having a central orifice, through which the reduced threaded end of the winding-bar *c* passes. The advantages of this structure are apparent, in that the invention may be easily applied to watches now in use without alter-

ing the pendant in the least, and the simplicity of the structure will at once recommend it to manufacturers.

It will be seen that when the bow and crown are engaged outward movement of the crown beyond the point at which it is held by the bow is impossible.

I claim—

In a stem setting and winding watch, the combination, with the pendant and a bow pivoted therein, of a longitudinally-movable winding and setting bar movable in or out, as the case may be, to wind or set the watch, having a crown with a concavity within which the end of the pendant fits, said bow and

crown being formed to engage with each other to hold the crown and winding-stem in, and a disk spring located within the crown and interposed between the same and the end of the pendant for moving the crown and stem outward, substantially as described. 20

In testimony whereof I have signed my name to this specification, in the presence of two subscribing witnesses, this 7th day of May, A. D. 1889.

EZRA C. FITCH.
